MACHINE FOR REMOVING SURFACE MOISTURE FROM LUMP MATERIAL

Joseph A. Albrecht, Buffalo, N. Y.

Application September 22, 1937, Serial No. 165,111

4 Claims. (Cl. 34—1)

This invention relates to a machine for removing surface moisture from lump material, and more particularly to a machine for removing adhering moisture from the outer surfaces of lumps of coal.

The main object of the invention is to provide a machine of this character which will accomplish this result in a sufficient degree at the lowest possible operating expense. Another object of the invention is to provide a machine of this character which will uniformly remove the moisture from substantially every portion of the surface of every individual lump of material. A still further object of the invention is to provide a machine of this character which will be low in initial cost and yet of high capacity and reliable in operation. Numerous other collateral objects of the invention and practical solutions thereof are disclosed in detail in the herein patent specification, wherein—

In the accompanying drawing:

Fig. 1 is a vertical, longitudinal section through the entire machine.

Figs. 2, 3 and 4 are vertical, transverse sections thereof, taken on correspondingly numbered lines of Fig. 1.

Similar characters of reference indicate like parts in the several figures of the drawing.

The main frame of the machine may be constructed in any suitable manner, for instance, by a pair of longitudinal foundation bars 10, 10a connected together transversely by a number of tie bars 11, 12 and 13, and supporting three pairs of posts 14, 14a; 15, 15a and 16, 16a to the top of which are secured a pair of upper longitudinal frame bars 17, 17a tied together by transverse tie bars 18, 19 and 20 at the upper ends of said posts.

Journalized horizontally and transversely in the front posts 16, 16a is a head drum or roll 21 around whose peripheral cylindrical surfaces passes the front turn or loop of a lower endless, squeezing belt 22 constructed of sponge rubber or similar, inherently-resilient material. The rear turn or loop of this squeezing belt 22 passes around a tail drum or roll 23 which is suitably journalized in the rear posts 14, 14a and is suitably power driven by any appropriate means. Intermediate of the head roll 21 and the tail roll 23, the upper operative stretch of this squeezing belt 22 is supported upon a lower, backing plate or table 24 which is curled forwardly and downwardly at its leading edge 25 so as to ensure that the squeezing belt 22 will not be cut or abraded as it travels horizontally and rearwardly onto and

over this backing plate. The latter rests at its opposite side edges upon a pair of horizontal, longitudinal angle irons 26, or other suitable supporting members, which are centrally secured to the intermediate posts 15, 15a and are attached at their opposite ends to the lower ends of two pairs of vertical hanger bars 27 and 28. The latter are suitably secured at their upper ends to the upper, longitudinal frame bars 17, 17a, as shown in Fig. 1.

Bearing against the outer surface of the lower squeezing belt 22, but not secured thereto, is a lower drying belt 29 which may be constructed of any fibrous or absorbent material such as thick, loosely woven canvas belting. This drying belt is adapted to absorb such surface moisture as may be present on the peripheral surfaces of the individual lumps 30 of lump material, such moisture as is absorbed being squeezed out of the lower or idle stretch of said drying belt by a pair of wringing or pressing rolls 31, 32 which engage with opposite sides of the lower stretch of the lower drying belt and are geared together at one of their corresponding ends by gears 33, 34 and are suitably power driven in any approved manner as, for instance, by a belt pulley 35. These wringing or pressing rolls are suitably journaled at their opposite ends in the lower parts of the intermediate posts 15, 15a. The moisture which is squeezed out of the drying belt 29 by the wringing rolls 31, 32 is caught by a substantially horizontal, transverse trough 36 and is conveyed away to the sewer or elsewhere through a discharge pipe 36a. To permit these wringing rolls 31, 32 to function properly without interference from the squeezing belt 22 the lower idle or return stretch of the latter is lifted up above the upper wringing roll 31 by a horizontal, transverse deflecting or separating roll 37 which is journaled at its opposite ends on the intermediate posts 15, 15a. This separating roll 37 also has the function of keeping a proper tension on the squeezing belt 22—suitable adjustment (not shown) for this purpose being provided, if desired, in any usual and well known manner.

Proper tension on the drying belt 29 is maintained by a horizontal, transverse smoothing roll 38 which is journaled at the lower ends of a pair of arms 39 that are pivoted at their upper ends by pins 40 on the intermediate posts 15, 15a. Adjustment of the tension on the drying belt 29 may be effected by a pair of weights 41 which are adjustable lengthwise of the arms 39 and are suitably locked in place after being adjusted.

The lump material 30 is fed in a constant stream

from a supply bin 42 to the operative front upper part of the drying belt 29. This bin 42 is provided with a vertical opening 43 which is sufficiently large to prevent any "arching" of the 5 lump material, the latter flowing out of said opening 43 onto an inclined chute 45 and thence down onto the drying belt 29. This ensures a uniform and continuous flow of lump material down the chute 45 without danger of stoppage 10 down the chute 45 without danger of stoppage due to "arching." In the present machine it is desirable to ensure that the lumps of material be never deposited on the absorbent belt 29 with one lump on top of the other. It is also desirable to turn such lumps as may happen to be lying 15 on an edge so that they will lie flatwise on the drying belt. To obtain both of these results simultaneously, a vertical, transverse levelling or evening plate 47 is arranged opposite the lower end of the chute 45, said levelling plate having 20 flanges 44 at its opposite ends to engage with the inner vertical faces of the chute 45, and being rendered vertically adjustable by the provision of vertical slots 48 and adjusting bolts 49. The levelling plate 47 is preferably inclined forwardly 25 so that any excess material will be directed upwardly by the levelling plate and overflow from the upper edge of the same and carried therefrom to the sides of the machine by overflow chutes 46.

Journaled horizontally and transversely in the 30 hanger bars 27, 28 is an upper, head roll 50 and an upper, tail roll 51 which are similar to the head and tail rolls 21, 23 in the lower part of the machine. Similarly an upper endless squeezing belt 52 passes with its front and rear turns 35 around these upper, head and tail rolls 50, 51, an upper drying belt 53 engages the outer side of the upper squeezing belt, a pair of upper wringing rolls 54, 55 engage with opposite sides of the upper inoperative or return stretch of the upper 40 drying belt, an upper separating roll 56 engages with the upper side of the inoperative stretch of the squeezing belt and deflects the same downwardly, and an upper smoothing roll 57 engages with the upper side of the upper return or inoperative 45 stretch of the upper drying belt. The smoothing roll 57 is carried by arms 571 which are pivoted on the main frame and this smoothing roll is pressed downwardly against the upper drying belt by weights 572 applied to these arms. 50 The upper wringing rolls are caused to turn in unison by intermeshing gears 573, 574 connected with the corresponding ends thereof. The water squeezed out of the upper stretch of the upper drying belt is caught in a trough 575 and carried 55 away by a chute 576. Intermediately of the upper, head and tail rolls 50, 51 is arranged an upper backing plate or table 59 which bears against the upper or inner side of the lower operative stretch of the upper squeezing belt and 60 forms the same function as the lower backing plate 24 relative to the lower squeezing belt.

The lower squeezing belt and its companion 65 drying belt are somewhat longer than the upper squeezing and drying belts and the lower squeezing and drying belts have their front parts extending beyond the corresponding parts of the upper squeezing and drying belts in order to permit the material delivery chute 45 and associated parts to overhang the front parts of the 70 lower squeezing and drying belts, as shown in Fig. 1. During the operation of the apparatus the upper operative stretches of the lower squeezing and drying belts are arranged close to the lower operative stretches of the upper squeezing 75 and drying belts and preferably the operative

stretches of these two drying belts actually engage each other.

Assuming that wet lumps of coal or similar water bearing material of a lumpy character are deposited by the feed device on the front receiving part of the lower drying belt and that the upper and lower squeezing and drying belts are operated so that their opposing operative stretches move at the same rate then the operation of the machine will be as follows: 10

As the lower squeezing and drying belts advance, the wet material deposited on the same will be carried underneath the upper squeezing and drying belts and move lengthwise of the machine with these belts. During this movement 15 the drying belts, due to the resilient character of the squeezing belts which supports the drying belts on their back sides, are deformed by the shape of the lumps of material which displace the drying belts so that the latter assume a contour which corresponds to that of the respective lumps of material and the same is virtually embedded in the nests or cavities made in the drying belts in conformity with the shape of the several lumps. While the lumps of coal or 20 the like are thus engaged on opposite sides by the drying belts these lumps are moved forwardly with these belts without however turning the lumps because the belts travel at the same rate 25 of speed. When the wet lumps are thus embedded between the upper and lower drying belts each of the lumps is practically engaged over its entire surface by these belts so that the latter operate in the manner of a blotter to remove 30 practically all the moisture from the lumps by 35 the time the same reach the rear turns of the drying and squeezing belts and permit the lumps to be discharged in a practically dry condition from the rear turn of the lower drying belt into a discharge chute 60 which delivers the dried 40 material to the desired place. 45

Any coarse particles broken from these lumps during the drying operation and clinging to the upper drying belt are scraped from the rear turn of the latter by a scraper 601 mounted on the main frame close to this turn which coarse material removed from the upper drying belt drops onto the adjacent rear part of the lower drying belt and is delivered by the latter to the discharge chute 60. In like manner any coarse particles 50 broken from the lumps during the drying operation and adhering to the lower drying belt will be removed from the latter by a scraper 602 which constitutes the inclined bottom of the discharge chute 60 and causes such coarse material 55 to join that which has been removed from the upper drying belt and to be carried away therewith.

Any small particles which may be detached from the lumps being dried and adhering to the upper and lower drying belts are brushed from these belts by rotary brushes 61, 62 engaging with the inoperative upper and lower stretches of these belts beyond the scrapers 601, 602 which brushes may be journaled on the adjacent parts 65 of the main frame and rotated in the proper direction by any satisfactory means. The small particles removed from the drying belts by the brushes 61, 62 are discharged into dust receiving 70 pans or chambers 63, 64 and from the latter these small particles are washed away by streams of water supplied by nozzles 67, 68 and carried away by spouts 65, 66 to any suitable place. 75

Inasmuch as the drying belts are distorted or wrinkled more or less by the lumps of wet coal

being embedded therein during the drying operation these wrinkles or distortions are removed by the smoothing rolls 57, 58 which engage with the respective upper and lower drying belts between the particle removing brushes 61, 62 and the pairs of wringing rolls 54, 55 and 31, 32 associated with the corresponding upper and lower drying belts. Each of these smoothing rolls is preferably crowned midway of its length or tapered from its central part toward its opposite ends, as shown in Fig. 4, so that the same upon engaging the respective drying belt will operate to distend or spread out the respective drying belt transversely into curved form from its longitudinal center toward its opposite side edges and thus restore these belts to a smooth condition preparatory to beginning another cycle of lump drying operations.

After the upper and lower drying belts pass the smoothing rolls 57, 58, the same are acted on, respectively, by the upper and lower pairs 54, 55 and 31, 32 of wringing rolls which remove from the idle or return stretches of these belts the water which has soaked into them during the operation of drying the wet lumps of coal or other material. This water is pressed out of the drying belts on the rear side of these rollers and to avoid accumulation of water in these localities the drying belts are so shaped adjacent to the wringing rolls that these belts will shed the water extracted from the same. This is preferably accomplished by tapering the lower wringing rolls 55, 36 from the center thereof to their opposite ends and tapering the upper wringing rolls 54, 31 from their opposite ends toward the center thereof, whereby the adjacent parts of each drying belt passing between these wringing rolls will be crowned lengthwise of its center and slope toward its opposite side edges, as shown in Fig. 2, so that the water will flow laterally from these belts into the troughs 58, 36 and be carried away, leaving the belts 53, 29 comparatively dry to continue their drying operation on the wet lumps of material under treatment.

If desired the two sets of drying and squeezing belts may be moved one faster than the other whereby the lumps of material between the opposing operative stretches while in engagement with this material will cause the same to roll or tumble and thus bring all parts of the surface of such lumps in contact with the drying belts and ensure removal of the maximum amount of water or moisture therefrom.

While the operative stretches are thus engaged with the lumps of coal or the like these belts yield and conform to the shape of these lumps so that in effect these lumps are nested in these belts and the latter practically enveloped or are wrapped partly around the lumps without however crushing the lumps or reducing the same in size, this being due to the cushioning and yielding capacity of the squeezing belts which back up the drying belts and support the same in whatever form they may assume.

It is therefore possible by the use of this apparatus to thoroughly dry the coal after the same has been washed and thus avoid freezing the same in a mass during the cold season and also furnishing a more acceptable product to the trade.

I claim as my invention:

1. A machine for removing moisture from the surface of lump material including two endless drying belts of fibrous material having opposing operative stretches which receive the material to be dried between them and remove the moisture therefrom, endless squeezing belts of resilient deformable material supporting said drying belts on the back thereof and permitting the latter to conform to the shape of the material being dried, wringing means for removing moisture from the idle stretch of each of said drying belts, and deflecting means for holding the idle stretch of each squeezing belt out of engagement from the idle stretch of the companion drying belt adjacent to said wringing means. 15

2. A machine for removing moisture from the surface of lump material including two endless drying belts of fibrous material having opposing operative stretches which receive the material to be dried between them and remove the moisture therefrom, endless squeezing belts of resilient deformable material supporting said drying belts on the back thereof and permitting the latter to conform to the shape of the material being dried, wringing means for removing moisture from the idle stretch of each of said drying belts, and smoothing means engaging the idle stretch of each of said drying belts in advance of said wringing means and operating to remove wrinkles or unevenness from said drying belts. 30

3. In a drying apparatus, the combination comprising a pair of conveyor belts disposed one over the other with the lower run of the upper belt substantially parallel to and adjacent to the upper run of the lower belt, each belt including a separable outer part composed of a capillary absorbent medium and an inner part having a resiliency and thickness sufficient to embed and surround a substantial area of articles fed between the belts, means for removing liquid from the absorbent outer parts of the belts, means for guiding and driving the belts so that the lower run of the upper belt and the upper run of the lower belt move in the same direction simultaneously, means for feeding articles between the adjacent runs of the two belts and means for receiving the articles discharged from the belts. 45

4. In a drying apparatus, the combination comprising a pair of conveyor belts disposed one over the other with the lower run of the upper belt substantially parallel to and adjacent to the upper run of the lower belt, each belt including a separable outer part composed of a capillary absorbent medium and an inner part having a resiliency and thickness sufficient to embed and surround a substantial area of articles fed between the belts, means for separating the inner and outer parts of said upper belt along the upper run thereof, means for separating the inner and outer parts of said lower belt along the lower run thereof, means for removing liquid from the separated absorbent parts of each of said belts, means for guiding and driving the belts so that the lower run of the upper belt and the upper run of the lower belt move in the same direction 55 simultaneously, means for feeding articles between the adjacent runs of the two belts and means for receiving articles discharged from the belts. 60
